(57) CLAIM

We claim the ornamental design for protective briefs for sexually-active persons, as shown and described.

DESCRIPTION

FIG. 1 is a perspective view of protective briefs for sexually-active persons showing our new design;

FIG. 2 is a front elevational view thereof;

FIG. 3 is a left side elevational view thereof, the right side elevational view being a mirror image thereof;

FIG. 4 is a rear elevational view thereof;

FIG. 5 is a top plan view thereof;

FIG. 6 is a bottom plan view thereof; and,

FIG. 7 is a cross section view of FIG. 2.

1 Claim, 4 Drawing Sheets

FIG. 3

FIG. 4

FIG. 5

FIG. 6

FIG. 2
